BRAKE

George McKinley Fitts, Washington, D. C.

Application September 7, 1935, Serial No. 39,652

6 Claims. (Cl. 188—78)

This invention relates to brakes and particularly to brakes of the internal expanding type. The present invention is an improvement over applicant's prior application Serial No. 326,969, filed December 19, 1928, and since issued as Patent No. 1,890,031.

It is an object of the invention to provide a brake of this type in which the actuating means expands brake shoes against a brake drum in such a manner as to produce equal amount of pressure at all points of contact between said brake shoes and brake drum.

It has been found that upon the expansion of a brake shoe against the brake drum there is wrapping of each of the shoes against the drum at a point farthest from its point of anchorage of the respective shoes. By wrapping, according to practical vernacular, it is meant that when the automobile wheel is turning the brake drum revolves and the brake shoe is actuated to contact the drums; and the instant the shoe makes contact with the drum there is a wrapping force between the shoe and the drum. In the present day brakes of this type, when expansion takes effect it is well known that it starts at the point farthest from its anchoring pin and the application of pressure between the shoe and the drum is greatest at this point, and the pressure gradually decreases as the revolving drum approaches the shoe in proximity of the anchoring pin, i. e., the pressure of the shoe and the drum near the anchor is much less than the pressure at the instant of expansion. This distorted application of pressure has the effect of causing the drum to become untrue or out of round, which upon continual wear between the drum and shoe results in an undesirable vibration upon application of the brake, the common occurrence of grabbing and squealing. It has also been found that when the drum becomes out of round, high and low spots occur which often cause the revolving drum to lock against the shoe upon energizing.

It is a further object of the invention to provide a series of floating brake shoes, each end of which is provided with an adjustable tension spring so as to keep the shoe in line with the circumference of the brake drum at all times.

It is a further object of the invention to provide the brake shoe with an elongated end, i. e., from the center of the pivot or anchoring pin the shoe has a long end and a short end. The long end of the shoe is the point at which the wrapping effect would ordinarily take place, but by so providing this elongated section the wrapping force between the shoe and the drum is equalized to allow the

shoe to be simultaneously expanded throughout, thus preventing any possibility of distortion between the drum and the shoe.

It is another object of the invention to provide shims at the ends of the shoe supports so as to give further adjustability to the brake shoe upon being assembled, i. e., to prevent any possibility of variance in clearance between the brake shoe and drum when being assembled.

It is a further object of the invention to provide spring-urged anchors midway between the brake shoe supports which serve to constantly urge the supports toward each other and thus give a sliding anchor.

It is a further object of the invention to provide a plurality of V-type shoes which are so constructed at their ends to give a complete interlinking fit between the two shoes. The advantage of this type of shoe is to allow for pressure at all points on the inner circumference of the brake drum, i. e., the pressure exerted between the ends of the brake shoes is equally as great as on the remaining portion of the shoe.

Further objects of the invention will appear from the following description taken in connection with the accompanying drawings which illustrate a preferred embodiment of the invention, and in which:

Fig. 1 is a vertical section through the brake mechanism, the section being taken on line 1—1 of Fig. 2 in a plane at right angles to the brake drum.

Fig. 2 is a vertical sectional view of Fig. 1, taken through Fig. 1.

Fig. 3 is a side view of one form of the brake shoe.

Fig. 4 is a rear view of Fig. 3 showing the specific V-type shoe.

Fig. 5 is cross-sectional view of the shoe taken on line 2—2 of Fig. 4.

Fig. 6 is a modified quarter-section of Fig. 1, showing the modified flat-type shoe.

Fig. 7 is top view of the shoes employed in Figs. 1—5, showing the V-shaped fitting ends.

Fig. 8 is a modification showing a two shoe flat type hydraulically actuated.

Referring in detail to the accompanying drawings, the invention includes a split brake drum 1 having screws 2 fastening it to the other drum 1'. Within the drum 1 and the drum support 3 are arranged two semi-circular brake shoe supports 4 and 5, each being slotted midway as at 6 for cooperation with a bolt 7 passing through the support and fixed by nut 8 into the backing plate 3, and serving to give the sliding movement of the shoe 5.

supports 4 and 5. Screws 9 are provided to hold the plate 10 to the bolt 7, said plate in turn assisting in the guiding of the shoe supports.

Within each slot 6 is located a coil spring 11 which bears at one end against the shoe support and the other end against the anchor bolt 1. The springs 11 are under compression and serve as retraction springs, i. e., to urge the shoe supports 4 and 5 constantly toward each other and away from the brake drum. The advantage of this particular method of anchoring the shoe supports will be referred to later in this disclosure.

Coil springs 12 and 12' are adapted to fit in apertures 13 for connecting the shoe supports and also serve to urge the supports 4 and 5 constantly toward each other. The ends of the springs are fitted in the apertures 13 to give a direct pull on the supports and eliminates any possibility of the supports swerving upon expansion.

Anchoring pins 15 serve as pivots for the brake shoes 14 carrying brake lining 16, said shoes adapted to be brought into contact with the drum 1 when the shoe supports are expanded for braking action, as hereinafter described.

The shoe 14, as clearly shown in Figs. 1 and 3, is composed of a long end 17 and a short end 18 i. e. if a center line is drawn through the anchoring pin 15 of the brake shoe which is perpendicular to outer circumference of the brake shoe or at right angles to the longitudinal axes of the pin, the end 17 of the shoe is longer from said center line than the opposite end of the shoe 18. See Figure 3. At each end of the brake shoe coil compression springs 19 are provided, which are adapted to bear at one end against the brake shoe and at the other end against the adjusting bolt 20 threaded into the shoe support 4. The bolt 20 carries a lock nut 21 so upon assembling the mechanism the shoe must be in perfect conformity with the drum and if any variance in clearance is present at any point between the shoe and the drum, the bolt 20 can be adjusted to allow for such clearance, and then locked by the nut 21 and thus give a uniform assembly throughout. The springs 19 also serve as equalizing means and aid in insuring that the pressure at all points along the brake shoe will be equal during its braking action against the drum.

The long end 17 of the V-type shoe 14 equalizes the wrapping force of the brake shoe upon expansion in that when the shoe 14 expands from the pivot point 15 of the shoe, the long end 17 balances the shoe by preventing the shoe from turning in a direction opposite to the direction of the arrow, as shown in Fig. 1, i. e., prevents the shoe from turning in an anticlockwise direction. The effect of this balancing is to equalize the pressure of the shoe at all points and thus give a perfect simultaneous expansion. Consequently by this simultaneous expansion there is an even and uniform wear on the brake lining overall. This can be readily seen from an application of the forces upon expansion. The long end 17 equalizes the overrunning torque and the reactive forces at the anchoring point 15.

As clearly shown in Figs. 1 to 5 inclusive, and in Fig. 7, the present invention involves the use of V-type shoes in lieu of the ordinary flat type, whereas the shoe 14 has two perpendicular sides. In Fig. 7 the ends of the shoe 14 are shown in a V-shape interfitting into each other, the V-shaped end 23 adapted to conform to the cut out

V-shaped portion 24 with the sections 25 and 26 likewise conforming. The advantage of this construction has been referred to above.

From the above it can be seen this equalization of forces, which results in a uniform wear on the lining, will prevent wrapping and the detrimental results which occur from it.

Between the adjacent ends of the semi-circular shoe supports 4 and 5 a double acting cam 27 is provided, which is pivotally mounted by a threaded bolt 28 for partial rotation on the brake drum support 3 and protected from slipping off by a washer plate 29. Each cam 27 is provided with an actuating lever 30 and the levers are connected by a link 31 so that upon operation of one of the cams the other cam will also be actuated in unison therewith. The cam 27 is actuated by a link and lever from the foot brake pedal or hand lever not shown.

On each adjacent end of the supports 4 and 5 are provided shims 32 held by screws 33. These shims are important in that they allow for adjustability of the supports 4 and 5 and can be increased to take any slight wear on the cam 27.

Fig. 6 shows a modification of applicant's device using the ordinary flat type shoe, in which 17^a is the elongated portion of the shoe. The principle of operation is identical as for that of a V-type shoe, as shown in the preferred embodiment.

Fig. 8 is another modification of the device showing the single brake shoe 14' mounted on each semi-circular member 4' and 5' constituting a two shoe type of brake. This modification discloses the use of an hydraulic cylinder 40 and piston 41 to actuate the lever 42, arm 43 and lever 44 which in turn drives the cams 48 anchored by pins 47 to simultaneously expand the shoe supports 4' and 5' which are anchored at 50. The brake shoes 14' are shown pivoted at 15' and the operation is identical with that disclosed for the preferred embodiment.

The invention operates as follows: Upon pressure being exerted from the brake pedal (not shown) the cams 27 are actuated to expand the semi-circular members 4 and 5 diametrically toward the drum 1, which in turn expands the brake shoes 14 and the brake lining 16 against the brake drum. The slot 6, screw 9, and spring 11 serve to guide the semi-circular members in a direct path of expansion. Upon coming in contact with the drum, the elongated end of the shoe equalizes the pressure between the shoe and the drum, the springs 19 assisting in equalizing the pressure and thus effecting a simultaneously expanded shoe.

I claim:

1. A brake comprising a drum, brake shoe carriers, V-type brake shoes, pivotally mounted on said carriers, said shoes having V-shaped ends interfitting into each other.

2. A brake comprising a drum, brake shoe carriers, pivoted brake shoes on said carriers, one end of each shoe from the center line of the pivot being longer than the other, said shoes having V-shaped ends interfitting into each other.

3. In combination a brake drum, a plurality of brake shoes associated with said drum, said shoes having V-shaped ends interfitting into each other.

4. A pivoted V-type brake shoe having V-shaped ends, one end of the shoe being longer than the other relative to a center line of the pivot.

5. A brake comprising a drum, a brake support, a pair of brake shoe carriers, guide means on said supports, springs bearing on said guide means and said carriers, springs connecting said

carriers urging them toward each other, a plurality of pivoted brake shoes mounted on each of said carriers, each shoe having one end from the center of the pivot longer than the opposite end, said longer end of the shoes positioned adjacent the opposite shorter end of the adjoining shoe, and a pair of equalizing springs between the shoe and carriers, and means for actuating said carriers toward the brake drum.

6. In combination a brake having a V-shaped brake drum, said drum being split into two sections, a plurality of pivoted brake shoes, having elongated ends relative to the center line of the pivot the elongated end of each shoe positioned adjacent the non-elongated end of the adjoining shoe. 5

GEORGE MCKINLEY FITTS.
